UNITED STATES PATENT OFFICE.

AARON SIMINOFF, OF LOS ANGELES, CALIFORNIA.

WEARING-APPAREL.

SPECIFICATION forming part of Letters Patent No. 758,940, dated May 3, 1904.

Application filed May 21, 1902. Serial No. 108,412. (No model.)

To all whom it may concern:

Be it known that I, AARON SIMINOFF, of 529 South Broadway, in the city of Los Angeles, in the county of Los Angeles and State of California, have invented certain Improvements 5 in Female Attire or Wearing-Apparel, of which the following is a full, clear, and exact description or specification, reference being had to the annexed sheets of drawings and to 10 the letters and figures marked thereon.

My invention has for its object mainly to avoid the construction of the skirts of dresses worn by females with a long slit or opening extending from and including the waistband 15 downward to enable (as hitherto constructed) the skirts of women's dresses to be passed over the larger part of the wearer's body and when passed thereover to be contracted so as to be fastened upon the body at the waist 20 of the wearer, the waist being usually of much smaller dimensions or circumference than is a woman's girth at the upper part of her body.

My invention has also for its object to prevent 25 the clothing worn underneath the skirt of females from being seen through the aforesaid long slit or opening in a skirt when from any cause whatever said slit or opening becomes unfastened or opened while being worn, 30 (as is frequently the case;) and my invention has also for its object to enable the waistband, which also is made endless—that is to say, without any opening or slit in it—to be fastened to any required dimension after the 35 skirt is placed upon the wearer's body, so that by simply fastening a hook and eye or equivalent device the skirt is maintained in its proper position and fit for being worn upon the body in the manner hereinafter described.

Upon the annexed drawings, Figure 1 is a perspective view of a skirt (looking at the back) constructed according to my present invention. Fig. 2 is a plan or top edge view 45 of the waistband of a skirt constructed according to my present invention. Fig. 3 is another perspective view of the skirt looked at from the back, wherein the waistband is shown folded and fastened by spring clasps 50 or snappers, which are so placed on the waist-

band as to enable it to be folded and fastened to accommodate its dimensions to the waist of the wearer, also showing the hook and eye for the final fastening of the waistband upon the wearer. Fig. 4 is a plan or edge view of 55 the waistband folded, as shown in Fig. 3, but drawn upon a larger scale than Fig. 3 in order to show the spring clasps or snappers for enabling the waistband and skirt to be folded and fastened to fit the wearer's body. 60 Fig. 5 is a front elevation of one half of one of the spring clasps or snappers, and Fig. 6 is a front elevation of the other half of one of the spring clasps or fasteners. Fig. 7 represents an end view of the hook and eye as 65 fastened to the nearest parts of the back of the endless waistband when the waistband is folded and fastened to the dimensions required to accommodate the waist of the wearer.

On reference to Figs. 1 and 2 it will be seen 70 that both the waistband A A and the part of the skirt B B to which the waistband A A is attached are continuous—that is to say, endless or without any slit or opening therein, such as is usually employed at the upper part 75 of the skirts of female attire. Upon the waistband A A there are fastened a series of pairs of spring clasps or snappers, each pair of which is marked by the same reference-number. For example, the thickened black 80 parts marked 1 1 upon Figs. 1 and 2 represent two halves of each spring clasp or snapper of the kind well known and in use and which is shown by the example drawn at Figs. 5 and 6. When the two halves of the spring 85 clasp or snapper 1 1 are fastened together or into or upon each other, then the waistband A A has a loop or fold in it between the parts at which the two halves of the clasp or snapper 1 1 are fastened, and the end of the fold 90 or loop thus formed has also attached to it one half of another spring clasp or snapper 4, which when folded against and entered into or upon the other half of the spring clasp or snapper 4 on the front part of the waistband, 95 as shown, causes that part of the waistband contained between the clasps or snappers 1 1 to be folded against and fastened within the front or side part of the waistband by the 100 clasps or snappers 4 4. Similarly, when the

clasps or snappers 2 2 on the other side of the back part of the waistband are fastened together and the other pair of snappers 3 3, which correspond to the pair of snappers 4 4 hereinbefore referred to and described, are fastened together then the part of the waistband folded and fastened by the snappers 2 2 is held similarly within the waistband by the snappers 3 3. In this manner, according to 10 the distance or distances between the respective pairs of snaps or clasps 1 1, 4 4, 2 2, and 3 3, the dimension of the waistband A A and the upper part of the skirt B B may be contracted or adjusted and fastened to fit any 15 size of waist of any wearer required, and when such waistband and waist are so adjusted and fastened the waistband and waist are finally fastened and adjusted upon the waist of the wearer by closing or engaging the 20 hook C into the eye D of these parts of the waistband A A which when folded and fastened in the manner hereinbefore described become situated at the center or at the side or at any other part of the waist of the 25 wearer and on being fastened together completely constitute a skirt correctly fitting the body of the wearer without any opening or slit therein of the kind usually employed in the construction of such skirts for women's 30 wear.

At Fig. 3 the skirt shown unfolded at Fig. 1 is shown in the folded position and as adapted to or as being worn upon the waist of any person to which the adjustment or fastening 35 to which the spring clasps or fasteners render it adapted for being worn, and the enlarged view, Fig. 4, shows the several clasps or snappers numbered as hereinbefore described and provided with a hook and eye C and D or 40 equivalent fastening in the position of the

several parts of the waistband and skirt as these are worn.

By placing more than one set of spring clasps or snappers upon the waistband in the order and arrangement hereinbefore described, but at different distances apart, the improved skirt and waistband may be folded and fastened into two or more dimensions of waist, so that one and the same waistband and skirt may be worn by one or more persons with equal facility by merely folding the waistband and fastening the clasps or snappers thereon to accommodate the waist of another or more than one other wearer, so that a single skirt may be by means of this invention worn with equal facility and fit by one or more persons.

Having now described the nature of my said invention and the best system, mode, or manner I am at present acquainted with for carrying the same into practical effect, I desire to observe in conclusion that what I consider to be novel and original, and therefore claim as the invention to be secured to me by Letters Patent, is as follows:

1. A dress-skirt provided on its upper portion with interlocking plait-forming devices and interlocking plait-holding devices.

2. A dress-skirt having a waistband provided on one side thereof with interlocking plait-forming devices, and on its opposite side with interlocking plait-holding devices.

In testimony whereof I, the said AARON SIMINOFF, have hereunto set my hand and seal, this 4th day of April, 1902, in the presence of two subscribing witnesses.

AARON SIMINOFF. [L. s.]
Witnesses:

WILLIAM E. MURRAY,
B. M. WILKINS.
